MEDICINAL VIAL

Carl B. Burnside, Indianapolis, Ind., assignor to Eli Lilly and Company, Indianapolis, Ind., a corporation of Indiana

Application February 5, 1954, Serial No. 28,852

Term of patent 14 years

(Cl. D58—6)

FIG. 1

Fig. 1 is a top plan view of a medicinal vial embodying my new design.

Fig. 2 is a side elevation of the vial.

The dominant feature of my design resides in the portions shown in full lines.

I claim:

The ornamental design for a medicinal vial, as shown and described.
